DESIGN FOR A CASING FOR PUNCHBOARDS

Frank J. Merhar, Portland, Oreg.

Application September 17, 1946, Serial No. 133,371

Term of patent 3½ years

(CL. D34—5)

To all whom it may concern:

Be it hereby known that I, Frank J. Merhar, a citizen of the United States, residing at Portland, in the county of Multnomah and State of Oregon, have invented a new, original, and ornamental Design for a Casing for Punchboards, of which the following is a specification, reference being had to the accompanying drawing, forming a part thereof.

Fig. 1 is a perspective view showing the ornamental design for a casing for punchboards from the right front quarter thereof showing my new design.

Fig. 2 is a view of the casing from the left rear quarter thereof.

I claim:

The ornamental design for a casing for punchboards, as shown.

FRANK J. MERHAR.
